UNITED STATES PATENT OFFICE.

DARWIN W. SHEPARD, OF DENVER, COLORADO.

ARTIFICIAL TIMBERING FOR MINE-TUNNELS.

No. 851,629.

Specification of Letters Patent.

Patented April 23, 1907.

Application filed May 25, 1906. Serial No. 318,732.

To all whom it may concern:

Be it known that I, DARWIN W. SHEPARD, a citizen of the United States, residing at the city and county of Denver and State of Colorado, have invented certain new and useful Improvements in Artificial Timbering for Mine-Tunnels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in artificial beams or timbers as well as the special arrangement of these timbers for tunnel work in mines or other localities where tunneling is required.

The invention will now be described in detail and will be fully understood by reference to the accompanying drawing in which is illustrated an embodiment thereof.

In this drawing, Figure 1 is a cross section of a tunnel showing the timbering in end elevation. Fig. 2 is a section taken through one of the artificial beams or timbers. In this view one of the beams is shown which when in use in the tunnel occupies a horizontal position at the top of the uprights. Fig. 3 is a similar view of one of the upright timbers. Fig. 4 is a view of one of the top timbers which is formed hollow, with a cavity open on its lower side. Fig. 5 is a perspective view of one of the beams which may be used for lagging or for forming the side walls of the tunnel outside of the upright beams. Fig. 6 is a fragmentary sectional view showing one of the uprights and the top and bottom beams connected therewith.

The same reference characters indicate the same parts in all the views.

Let the numeral 5 designate one of my improved artificial timbers which consists of a cement body 6 in which are embedded metal members 9 which are connected at their extremities as shown at 11 and bowed outwardly in opposite directions intermediate their extremities forming a sort of truss or double arch. Between these members 9 is located a spacing device 10 which retains the members in their normal position. These members 9 are bowed outwardly in the plane of the strain to which they are to be

subjected. For instance the timber shown in Fig. 2 is for use in a horizontal position or as shown at the top of the structure in Fig. 1. In this case the truss or metal arch members 9 are bowed upwardly and downwardly, thus greatly increasing their strain-resisting quality. In this case the metal members 9 are preferably flat and through their joined extremities are formed openings 12 which register with openings 13 formed in the cement body of the beam. These openings are to receive the ends of the metal rods or members which protrude from the extremities of the upright timbers. In the making of these beams, the metal truss members are prepared and the cement or concrete body while in a plastic state is poured into molds containing the metal parts so that after the body of the beam is hardened the metal parts are entirely concealed.

In the construction shown in Fig. 2, the members 9 are secured together at their extremities by rivets 9^a. In this view the members 9 are shown originally as two distinct and separate parts.

The upright timber which I will designate 15, is composed of the cement or concrete body 16 and two truss or arch-shaped members 17 bowed outwardly between their extremities, in the direction of the strain, the same as the construction shown in Fig. 2. The timbers 15, however, are to be subjected to lateral strain as they occupy an upright position; while the beams 5 are adapted to resist a vertical strain since they occupy a horizontal position. The truss members 17 are separated by a spacing device 18 whose extremities are curved to engage the said members which in this case are preferably composed of rods cylindrical or approximately cylindrical. As shown in Fig. 3 the two members 17 are formed from a single rod which is doubled back on itself the extremities of the members being joined by wiring them together as shown at 19. One of the members 17 as shown in Fig. 3 protrudes above the upper extremity of the beam as shown at 20 while both members protrude below the lower extremity as shown at 21. The upper end of the protruding part 20 as shown in the drawing is threaded to receive a nut 22 which is screwed down upon a washer 23 applied to the top of a member 5. The upper extremity 20 passes

through the openings 12 and 13 of the beam 5, while the protruding part 21 enters a recess 24 formed in a bottom beam 25 in which is embedded a flat bar 26. The lower and upper surfaces of the members 5 and 25, are provided with recesses or mortises to receive the extremities of an upright member 15.

The top and bottom members 5 and 25 and two upright members 15 one on each side of the tunnel, constitute a framing structure which will be located as often as required in the tunnel. To these frame structures is applied the necessary side and top lagging to prevent the surrounding natural walls of the tunnel from entering the latter.

As shown in the drawing the top lagging consists of beams 26 in which are embedded metal rods 27. These beams are provided with a longitudinal cavity 28 which opens on their lower surfaces. The lagging beams 26 which are placed at the extremities of the top members 5, receive the upper extremities 20 of the metal parts of the beams 16, whereby the latter are entirely concealed. The lagging for the side walls of the tunnel may be composed of beams 29 in which are embedded metal rods 30. The upright beams 15 of the timbering are provided at suitable intervals with angle irons 31 whose inner portions are embedded in the body of the beam while their outer extremities are turned upwardly forming supports for the lagging beams 29. Any desired number of these lagging beams may be employed according to the condition of the surrounding rock or material through which the tunnel is passing.

In view of the scarcity of wood for timbering mine and other tunnels, it is believed that my improved structure will be found exceedingly advantageous both from the standpoints of economy and durability.

Having thus described my invention, what I claim is:

1. A timbering structure for mines including a frame work composed of top beams and uprights at the extremities of the top beams, the body portion of each beam of the structure being composed of artificial stone in which are embedded metal members bowed outwardly between their extremities in the direction of the strain to which they are to be subjected.

2. A timbering structure for mines including a frame work composed of top beams and uprights at the extremities of the top beams, the body portion of each beam of the structure being composed of artificial stone in which are embedded metal members bowed outwardly between their extremities in the direction of the strain to which they are to be subjected, and suitable means for connecting the uprights with the top beam, substantially as described.

3. A tunnel timbering structure composed of top and bottom beams and uprights at the extremities of the top and bottom beams, the top and upright beams each being composed of cement substance in which are embedded metal members bowed outwardly between their extremities in the direction of the strain to which they are to be subjected, the upright beams being provided with outwardly protruding angle irons, side lagging beams supported by these angle irons, and top lagging beams which engage the top member of the structure.

In testimony whereof I affix my signature in presence of two witnesses.

DARWIN W. SHEPARD.
